UNITED STATES PATENT OFFICE.

FREDERICK GIETANNER, OF ST. LOUIS, MISSOURI, ASSIGNOR, BY MESNE ASSIGNMENTS,
TO GIETANNER ENGINEERING COMPANY, A CORPORATION OF MISSOURI.

VACUUM-UNLOADER FOR RAILWAY-CARS AND THE LIKE.

1,301,427.

Specification of Letters Patent. Patented Apr. 22, 1919.

Application filed December 27, 1917. Serial No. 209,022.

To all whom it may concern:

Be it known that I, FREDERICK GIETANNER, a citizen of the United States of America, residing at the city of St. Louis, State of Missouri, United States of America, have invented a certain new and useful Vacuum-
Unloader for Railway-Cars and the like, of which the following is such a full, clear, and exact description as will enable any one skilled in the art to which it appertains to make and use the same, reference being had to the accompanying drawings, forming part of this specification.

My invention relates to a vacuum unloading device, for unloading coal or similar material from railway cars or the like, and has for its object the production of a device which can be readily moved from end to end of the car, so that the entire contents of the car may be unloaded without disturbing the car.

Another object of my invention is to improve the details of construction of the unloading device.

In the accompanying drawings, which illustrate one form of unloading device made in accordance with my invention, together with a portion of a boiler room and railway car in connection with which the same is used, Figure 1 is a side view partly in section; Fig. 2 is an enlarged sectional view of the upper part of the unloading device; Fig. 3 is a front view; Fig. 4 is an enlarged side view of the lower part of the unloading device, partly in section; and Fig. 5 is an enlarged section taken on the line 5—5 of Fig. 4.

Like marks of reference refer to similar parts in the several views of the drawings.

10 represents the front wall of a boiler room adjacent to which is a track 11, upon which is a railway car 12 containing coal or other material to be unloaded and carried through windows 13 into the boiler room. Secured to the wall 10 of the boiler room is a track 14 upon which travels a carriage 15 supporting a sheave 16, around which passes a chain 17. The end of the chain 17 is secured to a conduit 18 extending from the interior of the car 12 through the windows 13 into the boiler room. The conduit 18 is provided with a blast nozzle 19, through which is forced steam, air or other fluid to create a vacuum in the conduit 18, in order

to convey the material. The flow of fluid 55 through the nozzle 19 is controlled by a valve 20 and the fluid is supplied to the nozzle from any suitable source by means of a flexible tube 21.

Secured to one end of the conduit 18 is 60 a discharge chamber 22, having an open bottom 23 through which the material is discharged, as best shown in Fig. 1 of the drawings. Arranged in the discharge chamber 22 is a deflecting plate 24 which is pivoted 65 at 25 and yieldingly held in position by means of a weight 26. A stop 27 limits the movement of the lower end of the plate toward the conduit 18. In order to prevent the plate 24 from striking against the rear 70 wall of the discharge chamber 22 I provide a block 28 of wood, or similar comparatively soft material. The steam or air used for carrying the material toward the conduit 18 passes upwardly through a discharge pipe 75 29. In order to prevent steam or air from passing directly up into the discharge pipe 29 I provide a baffle plate 30 extending from the top of the discharge chamber downwardly to a point below the end of the conduit 18, so that steam or air will be forced 80 to first pass downwardly before passing out through the pipe 29, thus insuring the discharge of the fine dust downwardly.

The lower end of the conduit 18 is provided 85 with a horizontal portion 31 having an up-turned end 32 into which the air is drawn by means of the vacuum created by the blast nozzle 19. The coal, however, is allowed to enter the horizontal portion 31 90 through either the upper opening 33, one of the side openings 34, or the bottom opening 35. In order that only one of these openings may be operative at a time I provide the horizontal portion 31 with a rotary 95 sleeve 36, having formed in it an opening 37, which is adapted to be brought into register with one of the openings 33, 34 or 35. In order to support the lower end of the conduit 18 I provide the horizontal portion 100 31 with a band 38 having an eye 39, which is attached to one end of a chain 40, which chain passes over a sheave 41 carried by a carriage 42, similar to the carriage 15 hereinbefore referred to. In order to secure 105 the chain 40 I provide the band 38 with a hook 43 adapted to be engaged with one of the links of the chain 40, and I also provide

the conduit 18 with a similar hook 44, adapted to engage with one of the links of the chain 17.

The operation of my device is as follows: 5 The car being in the position shown in Fig. 1, steam or air is allowed to enter the nozzle 19 thus forming a vacuum which will cause the material in the car to be carried through the conduit 18 and discharged into the boiler room, as best shown in Fig. 1. The sleeve 36 may be rotated to uncover the upper openings 33, one of the openings 34, or the bottom opening 35. The upper opening 33 will ordinarily be used, as I find 10 this gives the best results. In order, however, to convey the last material in the car it may be necessary to uncover the openings 34 or 35. It will be evident that by moving the carriages 15 and 42 along the track 15 the conveyer may be shifted from one end of the car to the other, thus discharging the entire contents without moving the car. When the conveyer is not in operation it 20 may be drawn up close to the track by means 25 of the chains 17 and 40.

Having fully described my invention, what I claim as new and desire to secure by Letters Patent of the United States is:

1. An unloading device comprising a normally horizontal tubular portion provided with an air inlet and an inlet for the material to be unloaded, an upwardly extending continuation of said tubular portion provided at its upper end with a discharge 30 chamber, and independently operated means arranged at the upper and lower ends of said upwardly extending portion for raising and lowering the device.

2. An unloading device comprising a normally horizontal tubular portion provided 40 with an air inlet and an inlet for the material to be unloaded, an upwardly extending continuation of said tubular portion provided at its upper end with a discharge chamber, and independently operated means 45 arranged at the upper and lower ends of said upwardly extending portion for raising and lowering the device, said means being independently movable laterally.

3. An unloading device, comprising a conduit 50 provided at one end with a discharge opening and at the other with an air inlet, and a sleeve arranged intermediate of the ends of the said conduit and provided with an inlet for the material to be unloaded, 55 said sleeve being rotatable to adjustably position said inlet.

4. An unloading device, comprising a conduit, means for forcing the material through said conduit, a chamber into which said conduit discharges, said discharging chamber having an outlet for the material at its lower end and a discharge opening for the air at 60 its upper end, a yielding deflecting plate against which the material strikes, the inlet and discharge openings being arranged 65 at the same side of said deflecting plate, and a baffle plate dividing the upper portion of said discharge chamber into two parts, one of which communicates with the air discharge, and the other with the end of said conduit.

In testimony whereof, I have hereunto set my hand and affixed my seal.

FREDERICK GIRTANNER. [L. S.]
